UNITED STATES PATENT OFFICE.

WILLIAM C. ORGAN, OF OAKLAND, CALIFORNIA.

WINDOW-SHADE ADJUSTER.

SPECIFICATION forming part of Letters Patent No. 790,703, dated May 23, 1905.

Application filed February 14, 1905, Serial No. 245,564.

To all whom it may concern:

Be it known that I, WILLIAM C. ORGAN, a citizen of the United States, residing at Oakland, in the county of Alameda and State of California, have invented new and useful Improvements in Window-Shade Adjusters, of which the following is a specification.

My invention relates to a means for adjusting window-shades with relation to the windows to which they are attached so that such shades may be bodily raised or lowered with relation to the window-opening and by such movements either placed at the top of the window or at some point intermediate of its height and independent of the rolling and unrolling of the shade.

My invention consists in tubular guides fixed to the lower part of the window-frame and rods slideable in said guides connected together at the top and having sockets for the reception of the pivot and non-turnable pins, respectively, of what are known as "spring shade-rollers."

My invention comprises details of construction, which will be more fully explained by reference to the accompanying drawings, in which—

Figure 1 is a perspective view of my invention. Fig. 2 is a section of one end of the shade-roller and the socket-piece.

Various devices have been employed by which shade-rollers may be placed at different heights with relation to the window-opening, the object being to provide for the entire cutting off of the light when the shade is unrolled from the top of the window or for the admission of light above the shade when the roller has been lowered below the top of the window.

My invention is designed to provide an improved and easily-adjustable device for this purpose which is especially applicable to spring shade-rollers.

As shown in the drawings, A is a window-frame of any description.

2 represents vertical tubes fixed to the casting at any desired point with relation to the moving sashes. These tubes are preferably fixed inside of the inside stops and may extend from the bottom upward to one-half or

less of the height of the window-opening. Within these tubes rods 3 are slideable, and upon the upper ends of the rods are fixed the blocks or end pieces 4. These blocks 4 are here shown as connected by a rod 5, which 55 may have right and left screw-threads at its opposite ends and may thus be screwed into the blocks, the screw-threads terminating in shoulders which will limit the distance to which the rod is screwed, so that the rods 3 60 will stand parallel and slide freely within the guide-tubes 2. Below the rod 5 openings are made in the faces of the blocks 4. One of these openings is cylindrical and is adapted to receive the pivot-pin 6 of the shade-roller 65 7, which projects into and is turnable in this hole.

The shade-roller is of the usual well-known form, having a spiral spring within it, and the opposite end of the roller has a flattened pivot, as at 8, which enters a correspondingly flattened or rectangular opening in the block 4 at that end, so that the shaft to which the spring is fixed is held stationary, while the roller is turnable upon it.

The shade 9 has the usual cord or chain 10 fixed to its lower bar, so that it may be pulled down by the chain, and is held at any point of adjustment by the pawls usual to this class of shade.

11 is a cord having one end connected with the center of the bar 5, passing up over a pulley 12 and thence down, and having at its end a ring or other connection, as at 13, by which the cord may be operated. The pulley 12 is of 85 that class having a notch in one side and adapted to bind upon the cord and hold it at any point when the cord is drawn out of line and to one side of the pulley. By means of this cord it will be seen that the bar 5, with the 90 sliding rods, and the heads 4, in which the shade is journaled, may be raised to the top of the window, and when at this point the shade may be pulled down to exclude all the light, or the rod may be lowered until the top 95 of the shade is at any desired point above the ends of the guide-tubes 2, and the shade may thus be suspended at any desired point between the top of the window and the upper ends of the guide-tubes. Thus when the shade 100

is in this position by pulling it down the light would be excluded to any extent from the lower part of the window, while any desired amount of light may be allowed to enter from 5 the top of the shade.

The device is easily applied to windows and is very simple and effective for the purpose desired.

Having thus described my invention, what 10 I claim, and desire to secure by Letters Patent, is—

1. The combination with a window or like frame of fixed tubular vertical guides, rods 15 slidable in said guides having heads upon the upper ends, a shade-roller having its bearings in said heads, a pulley fixed at the top of the window-frame, and means whereby the heads and the shade may be raised or lowered with relation to the window-opening.

2. A shade-roller attachment for windows 20 consisting of vertical tubular guides fixed upon each side of the lower part of the window-frame, rods slidable in said guides having heads at the upper end, a connecting-bar by 25 which said heads are united, a cord having one end centrally attached to said bar, a lock-

ing-pulley in the top of the window-frame over which said cord passes whereby the slide-able frame may be raised lowered and fixed at any point, and a shade-roller having bear- 30 ings in the heads of the sliding bars below the transverse connecting-bar.

3. A shade-roller attachment for windows 35 consisting of vertical tubular guides fixed upon each side of the window-casing, a frame con-sisting of two vertical rods slidable in said tubes having a transverse connecting-bar at the top, a shade-roller having its ends sup-ported in said frame below the transverse bar, a cord centrally connected with the bar, a 40 locking-pulley fixed to the top of the window-casing over which said cord passes, and an at-tachment at the opposite end of the cord by which the shade-carrying frame may be raised or depressed.

In testimony whereof I have hereunto set my hand in presence of two subscribing wit-nesses.

WILLIAM C. ORGAN.
